UNITED STATES PATENT OFFICE.

JOHN WILLIAM MERTZ, OF MOUNT CLEMENS, MICHIGAN.

RHEOSTAT.

No. 886,230.

Specification of Letters Patent. Patented April 28, 1908.

Application filed January 14, 1908. Serial No. 410,721.

To all whom it may concern:

Be it known that I, JOHN WILLIAM MERTZ, a citizen of the United States, and a resident of Mount Clemens, in the county of Macomb and State of Michigan, have invented a new and improved Rheostat, of which the following is a full, clear, and exact description.

My invention relates to rheostats suitable for general use, and more particularly to a type of rheostat of special service in connection with arc lamps for the production of moving pictures.

The more particular purpose of my invention is to give the operator a more extensive control over the current so that he can closely graduate the resistance and govern it completely within wide limits.

My invention further relates to certain details in construction whereby the general efficiency of the rheostat is increased.

Reference is to be had to the accompanying drawings forming a part of this specification, in which similar characters of reference indicate corresponding parts in all the figures.

Figure 1 is a fragmentary front view of the rheostat complete, the lower portion of the figure showing the coils and the upper portion showing the switch handles provided with hand switches for manipulating the resistance; Fig. 2 is a fragmentary rear view of the rheostat, this view showing particularly the back of the switch handles and the manner of connecting the coils to the hand switches; Fig. 3 is a vertical section upon the line 3—3 of Fig. 2, looking in the direction of the arrow and showing how the coils and the switch handles are supported upon the framework; and Fig. 4 is a diagram of the switches, the windings and electrical connections.

Two flat bars 5, 6 constitute respectively the top and bottom pieces of the framework, and are connected together by tubular posts 7, 8 secured in position by bolts 7^a, 7^b. By loosening these bolts the flat bars may be disconnected from the tubular posts so as to disassemble the parts. Feet 9 are bolted to the bottom bar 6 and serve to support the latter out of engagement with the floor or other surface upon which the rheostat rests. A panel board is shown at 10 and is secured upon supporting rods 11 bent substantially into L shape (see Fig. 3) and provided with

portions 12 which are secured to the upper bar 5 by aid of bolts 13. The panel board thus projects outwardly a little from the bar 5 and is thereby rendered more convenient and accessible to the operator. 60

Mounted upon the panel board 10 are binding posts 14, 15 which are connected with conductors 16, 17 through which the current flows in and out of the rheostat. A metallic strip 18 connects the binding post 14 with a pivot post 20, the latter being provided with a binding post 19 (see Fig. 2) upon the back of the panel for this purpose. Upon the pivot post 20 is mounted a switch knife 21 free to swing upon the pivot post as 70 a center. A contact fork 22 is mounted above the pivot post 20 and a contact fork 23 is disposed below this post and adapted to be engaged by the switch knife 21. A handle 24 is mounted upon the switch knife 75 for turning it upon the pivot post 20.

A number of other pivot posts 25, 26, 27, 28 and 29 are disposed in a row, and mounted respectively upon them and free to swing are switch knives 30, 31, 32, 33 and 34. Disposed partially within the paths of these switch knives are contact forks 35, 36, 37, 38, 39, and mounted upon the switch knives for the purpose of manipulating them are handles 40, 41, 42, 43, 44, which, like the handle 24, are of insulating material. 85

The pivot post 29 is provided with a binding post 29^a (see Fig. 2) upon the rear face of the switch panel and this binding post is connected by an insulated wire 45 with a similar 90 binding post 28^a, the latter being connected with the pivot post 28. The contact forks 37, 38 are similarly provided with binding posts 37^a, 38^a (see Fig. 2), these binding posts being connected together by a metallic 95 strip 46. The pivot posts 26, 27 are provided with binding posts 26^a, 27^a, connected together by a metallic strip 47. The pivot post 25 is provided with a binding post 25^a which is connected by an insulated wire 48 100 with the binding post 15. The contact forks 23 and 35 are provided with binding posts 23^a, 35^a, which are connected together by an insulated wire 49.

I use two groups 50, 51 of resistance windings, each group consisting of any convenient number. In the particular instance here described, there are six windings in each group. The group 50 is located upon the front of the machine, that is, nearest the 105

110

switch panel 10, and its windings are designated 58, 59, 60, 61, 62, 63. The windings of the rear group are designated as 52, 53, 54, 55, 56, 57.

5 For the purpose of supporting the various windings each is connected with a metallic clip 64 having spring arms 65 of a general U shape and adapted to grip a spool 66 of insulating material. The spools 66 are arranged 10 in pairs and held in position by bolts 67 which pass directly through the flat bar 5. Similarly clips 68 engage spools 69 which are arranged in pairs and supported upon bolts 70 (see Fig. 3). The arms 66 are malleable 15 and are bent around the spools or clenched thereupon, so as to hold the windings.

The windings 52, 53, 54, 55, 56, 57, constituting the group 51, are connected together 20 in series by short pieces of wire 71, 72. An insulated wire 73 leads from the binding post 23^a of the contact fork 23 to the winding 52. Another insulated wire 74 connects together 25 the two groups 50, 51, and in doing this, connects in series the two adjacent windings 57, 58. A wire 75 connects the winding 58 and wire 74 with the contact fork 22 which is provided for this purpose with a binding post 22^a (see Fig. 2). A wire 76 connects the winding 63 with the binding post 15. A wire 77 30 leads from the lower end of the coil 62 to the contact fork 36. The windings of the group 50 are connected together by short wires 78, 79, 80, 81 and 82, as will be understood from the lower left-hand portion of Fig. 4. A wire 83 connects the pivot post 26 with the upper end of the winding 61. A wire 84 establishes communication between the lower 35 end of the winding 60 and the contact fork 38. A wire 85 connects the lower end of the winding 59 with the contact fork 39. The upper end of the winding 59 is connected by a wire 86 with the pivot post 28.

For convenience some of the wires, such as 40 82, 85, 86, are led downwardly through the tubular posts 7, 8, being thereby hidden and also protected.

The switch panel 10 is made preferably of slate, but I do not limit myself to the use of this material, nor, indeed, to the use of any 45 particular material for any part of the device. The resistance windings are made preferably of steel.

The operation of my device is as follows: I will suppose that at the start all of the 50 switches are open. The connection may be traced diagrammatically in Fig. 4. For convenience in tracing the various circuits, I will omit specific reference to the various binding posts, clips and the like, constituting 55 portions of the current's path, and will refer chiefly to the windings and wires constituting the essential parts of the circuits. By manipulating the switches I am enabled to give a great range to the resistance offered by the 60 rheostat as a whole. Suppose, first, that I

desire the rheostat to afford a maximum of resistance. I simply lower the handle 24 so that it engages the contact fork 23. The other switches remaining open, the circuit may now be traced as follows: conductor 16, strip 18, pivot post 20, switch knife 21, contact fork 23, wire 73, windings 52, 53, 54, 55, 56, 57, in series through their connecting wires 71, 72, next through wire 74, winding 58, wire 82, winding 59, wire 81, winding 60, 70 wire 80, winding 61, wire 79, winding 62, wire 78, winding 63, wire 76, binding post 15 to wire 17.

It will be noted that all twelve of the windings are thus thrown in, and consequently the resistance is at a maximum. Hence, the current is cut down to a minimum, and if used in lighting, the light is weak.

Suppose, now, that the operator wishes to 80 suddenly increase the light to a slight extent. He simply raises the handle 41, thus causing the switch knife 31 to engage the contact fork 36. The circuit above traced in series throughout all of the windings is not broken, 85 but the contact of the switch knife 31 with the contact fork 36 diminishes the total resistance of the circuit. This is because when the current gets to winding 61 it need not all pass through the wire 79, but a portion can 90 follow a shorter path, to wit, wire 83, pivot post 26, switch knife 31, contact fork 36, wires 77, 78, 63, 76, post 15 and conductor 17. The net result is that the current has, during 95 a part of its course, a double path, and this, under Ohm's law, necessarily lowers the total resistance, though, as it affects a comparatively small part of the circuit, the lowering in resistance is comparatively slight. To state the same thing another way, the 100 current splits and part passes in series through all of the windings, the other part skipping winding 62. Similarly, if the switch handles, 42, 43 and 44 be raised so that the switch knives 32, 33, 34 engage the 105 contact forks 37, 38, 39, the windings 61, 60, 59, are affected like the winding 62, the total resistance being thus lessened. For instance, if the switch handle 44 be raised, we have the same circuit as before, to wit, one traversing 110 all of the windings in series, but from this circuit we have a shunt circuit which skips the winding 59. With all of the switch handles 41, 42, 43, 44 raised, the resistance of the group 50 is very low, being not much 115 more than half the resistance of this group when the switch handles 41, 42, 43, 44 are all down. Since, however, the windings of the group 51 are always in circuit and are always in series with each other, with reference to 120 the current through them, the total resistance caused by a movement of any one of the switch handles 41, 42, 43, 44 is not very great. Suppose, now, that we raise the switch handle 125 24 so that the switch knife 21 engages the 130

contact fork 22. The current now passes through the group 50 only, the circuit being as follows: conductor 16, binding post 14, strip 18, switch knife 21, contact fork 22, 5 wire 75, winding 58, wire 82, winding 59, wire 81, winding 60, wire 80, winding 61, wire 79, winding 62, wire 78, winding 63, wire 76, binding post 15, to conductor 17. The current thus passes in series through the 10 group 50 alone. If, now, the current passing through this group is too weak (as indicated, for instance, by weakness in the lights), the switch handles 41, 42, 43 and 44 are raised in succession, thus allowing more current to pass. If the lights are still too dim, I raise the switch handle 24. This doubles the amount of current which would pass if the switch handle 24 alone were raised.

Care must be exercised not to have the 20 switch handle 24 lowered at the time when the switch handle 40 is raised, for the reason that this would form a short circuit. It may sometimes happen, however, that a short circuit is needed, and in this event the two 25 switches mentioned may be given the relation thus stated.

It will be noted that the switch handles 41, 42, 43, 44 may be operated independently for the purpose of reducing the total resistance 30 of the group 50. If only one of these switch handles be raised, the total resistance is not affected very much, but as all four, or any less number of them, may be raised at will, the resistance may be varied considerably, 35 this effect being entirely independent of whether the two groups are connected in series or in parallel.

As the switches represented by handles 41, 42, 43, 44 are used for the purpose of breaking up the series connections, I find that workmen and electricians designate these switches as "Series Busters". I therefore designate them by the legend "Bus" as indicated in Figs. 1 and 4. The switch represented by the handle 40 being used mainly for the purpose of connecting the groups 50, 51 of windings in multiple with each other, I designate as the multiple switch and in practice usually mark it with the legend "Mul" 45 (see Figs. 1 and 4). The switch represented by handle 24 being used for either connecting the windings in series or in single multiple, I provide it with appropriate legends "Series" and "Single-Multiple", as shown by the figures just mentioned.

Having thus described my invention, I claim as new and desire to secure by Letters Patent:

1. In a rheostat, the combination of an upper bar, a lower bar, tubular posts connecting said bars together, resistance windings disposed intermediate said upper bar and said lower bar, and electrical connections for said

windings, some of said electrical connections extending through said tubular posts. 65

2. In a rheostat, the combination of a pair of bars provided with openings, tubular posts extending through said openings, fastening members for securing said tubular posts within said openings so that the parts may be readily disassembled, and windings supported upon said bars. 70

3. In a rheostat, the combination of a winding, clips connected with said winding and provided with U-shaped portions of malleable metal, insulating members engaged by said U-shaped members, said U-shaped members being bent so as to hold on to said insulating members, and connections for said windings. 75

4. In a rheostat, the combination of a framework, windings supported upon said framework and provided with electrical connections, a switch panel, and rods connected with said switch panel and bent into L shape, 80 said rods being connected with said framework, and a plurality of switches mounted upon said switch panel and connected with said windings. 85

5. In a rheostat, the combination of a framework, a plurality of resistance windings supported upon said framework, a switch panel, switches mounted upon said switch panel, and connections from said switches to said windings, the arrangement of said connections being such that by moving said switches said windings may be connected either in series or in parallel as desired. 90

6. In a rheostat, the combination of a framework, a group of windings mounted upon one side thereof and connected in series with each other, a group of windings mounted upon the other side thereof and connected also in series with each other, and means controllable at will for connecting the windings 100 of said last-mentioned group so as to form an additional short circuit from one of said last-mentioned windings to another, thereby diminishing the total resistance of all of the windings. 105

7. In a rheostat, the combination of a plurality of windings connected in series, and means including a plurality of hand switches for short circuiting said windings so as to divide the current flowing through them, a portion of said current passing in series through all of the windings, and a portion of said current being shunted off so as to skip a portion of said windings. 110

In testimony whereof I have signed my 120 name to this specification in the presence of two subscribing witnesses.

JOHN WILLIAM MERTZ.

Witnesses:
